PLACE MAT

Oscar C. Elledge and Harold R. McCray,
Columbus, Ohio

Application May 13, 1952, Serial No. 19,704

Term of patent 3½ years

(Cl. D92—26)

To all whom it may concern:

Be it known that we, Oscar C. Elledge and Harold R. McCray, citizens of the United States, residing at Columbus, State of Ohio, have invented a new, original, and ornamental Design for a Place Mat, of which the following is a specification, reference being had to the accompanying drawing, forming a part thereof.

Fig. 1 is a top elevational view of a place mat showing our new design; and

Fig. 2 is a side elevational view of the place mat shown in Fig. 1.

We claim:

The ornamental design for a place mat, substantially as shown.

OSCAR C. ELLEDGE.
HAROLD R. McCRAY.
